PERMUTATION LOCK

Harry C. Miller, Fairfax, Va.

Application March 26, 1949, Serial No. 83,548

13 Claims. (Cl. 70—129)

1 This invention relates to improvements in permutation locks, commonly referred to as combination locks.

Locks of the type commonly referred to as combination locks are, of course, very well known. Also it is generally known that such locks depend for their operation upon the alignment of a plurality of elements in a preselected manner which permits the operation of a bolt. These elements are usually in the form of discs, commonly called tumblers, each of which is provided with a notch or recess, called a gate, the alignment of the gate determining when the bolt can be moved. It is common for these locks to be provided with three discs, although more could be used. The security of such locks is dependent upon the fact that the number of orders or permutations of the possible relative positions of each disc before all of the gates come into register, which gives the correct combination, is so large that the chances of these notches or gates being aligned by a person not familiar with the combination is so small as to be negligible.

The tumblers are operated through means of a driver wheel which also has a special gate. An element called a fence extends transversely across the edges of all of the tumblers and is adapted to drop into the gates when all of the gates in the tumblers are in alignment and when the driver wheel is manipulated to permit the fence to drop. Conventionally, the fence is held in such a position that it is slightly spaced from the outer peripheries of all of the tumblers. However, because of the difficulty in manufacture, it is almost impossible to manufacture all of the parts, including the tumblers, to such close tolerances that there will be the same slight difference in the space between the outer edges of the different tumblers and the fence. Accordingly, by a very careful manipulation of the driver wheel to a position such that the fence drops against the edge of the highest tumbler, a skilled person can detect by feel or by a very minute sound or click when one of the gates is aligned with the fence. Then by continuing to manipulate the driver wheel by means of the dial, the gate of the next highest tumbler can be aligned with the fence and, therefore, with the gate of the first tumbler and so on until the correct combination is found and the security of the lock is broken. Accordingly, heretofore, because of the defects generally mentioned above, the security of a so-called combination lock against a skilled person has been limited. In accordance with the present invention, means is provided for closing the special

gate in the driver wheel. Furthermore, the special gate can be opened only when this driver wheel gate is substantially aligned with the fence. This avoids the defect of the prior devices in that the driver wheel cannot be turned sufficiently to manipulate the tumblers when the gate is open. Also, in order to insure that the tumblers cannot be vibrated or walked by oscillating the driver wheel over its limited arc of movement, interlocking means are provided in the form of serrations on the fence and on the peripheries of the tumblers so that as soon as the driver wheel gate is opened the fence rests on the tumblers, the serrations being inter-engaged thereby making manipulation of the tumblers practically impossible.

The primary object of the present invention is to provide a combination lock in which a manipulation of the dial will not give any indication of the position of the gates in any of the tumblers.

Another object is to provide a combination lock with a driver wheel having means for selectively closing the gate in the driver wheel and for permitting rotation of the driver wheel only when the gate is closed so that the fence is held away from the peripheries of the tumblers.

Another object is to provide a combination lock in which the driver wheel cannot be rotated to manipulate the tumblers when the driver wheel gate is open.

Another object is to provide a combination lock in which the driver wheel cannot be rotated to manipulate the tumblers when the driver wheel gate is open and having interlocking means between the tumblers and the fence to prevent the walking of the tumblers when the driver wheel gate is open.

A still further object is to provide an improved combination lock in which the fence can be held in spaced relation to the outer edges of all of the tumblers until the gates in all of the tumblers are brought into alignment.

Another object is to overcome defects of prior combination locks by providing means which holds the fence in slightly spaced relation with respect to the edges of the tumblers, which means can only be operated when the gates in the various tumblers are properly aligned in accordance with the correct combination.

Another object is to provide an improved combination lock in which the perfections of the manufacture of the elements will not give any audible indication as to the relative position of the tumblers.

Other and further objects will become readily

apparent from the following description when considered in connection with the accompanying drawings, illustrating an embodiment of the invention, and in which:

Figure 1 is a vertical section on line 1—1 of Figure 2 of a lock made in accordance with the present invention;

Figure 2 is the vertical section on line 2—2 of Figure 1; and

Figure 3 is a partial vertical section showing 10 the parts of the lock in a different position from that shown in Figure 2;

Figure 4 is a partial sectional view on line 4—4 of Figure 1;

Figure 5 is a partial sectional view on line 5—5 15 of Figure 2;

Figure 6 is a partial view showing a modified form of the gate closing means;

Figure 7 is a view similar to Figure 6 showing the modified driver wheel in a different position; and 20

Figure 8 is an exploded perspective view of the modified driver wheel and gate closing means.

Figures 9 to 11 inclusive, are partial views showing various positions of the key-operated gate-closing means and showing the relative positions of the fence; and

Figure 12 is a partial vertical section showing the engagement of the fence with one of the tumblers, near its gate.

The illustrative drawings show a conventional combination lock modified in such a manner as to permit the application of an embodiment of the present invention. The conventional lock comprises a casing 1 connected by a press fit to a hollow sleeve 2 which projects through a door 3. In the casing a plurality of tumblers 6, 7 and 8 are rotatably mounted on a cylindrical boss integral with the casing, the boss being substantially co-extensive with the sleeve 2. Secured to the outer end of the sleeve 2 is a suitable escutcheon plate 9. The casing is secured to the door 3 by the sleeve 2 and suitable screws. Inside the sleeve 2 is a shaft 11, the inner end of which has rotatably fixed thereto a driver wheel 12, the opposite end of the shaft 11 having a dial 13 fixed thereto. As will be more clearly explained hereinafter the dial and its hub constitute the means through which the tumblers 6, 7 and 8 of the combination lock are manipulated.

Each of the tumblers 6, 7 and 8 are of conventional construction and are divided in two parts, an inner part serving as a hub and an outer part having a suitable notch or gate 6a, 7a, and 8a, respectively, it being understood that all of the gates of the tumblers must be in proper alignment in order to operate the bolt of the lock. Conventional means are provided for changing the relative position between the hub portion and the outer portion of the tumblers for the purpose of changing the lock combination. Suitable fixed washers having small detents which engage a recess 2a in the sleeve 2 are placed between the hubs of adjacent tumblers so that from the standpoint of mechanical friction each of the tumblers is completely isolated from the other. One of such washers is indicated at 16. Between one side of the washer and the next adjacent tumbler is a flyer 17 having an outwardly projecting detent 17a. The annular portion of the flyer 17 serves as a spacer while the outwardly projecting detent 17a serves as an element through which one of the tumblers is driven by a laterally projecting detent on the next adjacent tumbler. This construction just described in general is conventional and therefore further details are not considered necessary.

The driver wheel 12 is screw-threadedly secured to the shaft 11 and a suitable key 21 is provided to lock the driver wheel in non-rotatable position on the shaft 11. The driver wheel is provided with a lateral projection 22 which is adapted to engage the outwardly extending detent on the flyer between it and the tumbler 8. It will be readily understood that when the dial 13 is rotated to rotate the driver wheel 12 that the projection 22 will drive the tumbler 8 and through the intermediate flyer between the tumbler 8 and tumbler 7 the latter will be driven and so on, including the tumbler 6. It will also be well understood that the gates 6a, 7a and 8a of the respective tumblers may be brought to register with each other in the well known manner when the proper combination is obtained by turning the knob 13 first to the right, lining up the gate in one tumbler, then to the left lining up the gate in the second tumbler, and then to the right again lining up the third tumbler, and so on, if a lock with more than three tumblers is used.

The lock is provided with a bolt 23 which is adapted to slide in a suitable guide formed in the casing 1, the bolt 23 being operated by a fence-lever 24 pivotally attached thereto by a screw 26. A suitable spring 30 is provided for the purpose of urging the fence-lever 24 toward the tumblers. The fence-lever 24 is provided with a laterally projecting arm, commonly referred to as a fence 27, which is adapted to engage the gates when the tumblers are in proper relative positions. The driver wheel 12 is also provided with a special gate 12a, the shape of which is complementary to the shape of a depending boss 28 on the fence-lever 24. The lower point of the boss 28 normally rides on the outer periphery of the driver wheel 12. The periphery of the driver wheel 12 and the size of the boss 28 is such that the fence 27 is slightly spaced from the outer periphery of all of the tumblers. As is usual, the lock is provided with a suitable device to prevent tampering so that in the event that an attempt is made to drive the shaft 11 inwardly toward the casing, the bolt 23 would be locked in position. To this end, a suitable element 31 having an end portion 31a which engages the outer face of the upper tumbler 8 is provided. The element 31 is pivoted on screw 33 and is provided with a curved end 31b which partially encircles a locking pin 34 when the parts 50 of the lock are in normal position. The locking pin 34 is adapted to slide in a suitable guiding recess in the casing 1 and is provided with a C-shaped washer which engages a groove in the pin 34. One side of the washer engages the curved end portion 31b of the element 31 and a suitable spring 37 is provided for normally urging the pin 34 in upward position where it could engage a notch in the underside of bolt 23. It will be readily apparent that in the event the end 31a of the element 31 is moved, as when an unauthorized person attempted to disturb the parts of the lock, the element 31 would pivot around the screw 33 and its opposite end 31b would become disengaged from the washer 36, thereby permitting the spring 37 to urge the locking pin 34 into such a position as to engage the recess in the underside of the bolt 23 so that the latter could not be moved.

The construction described so far is conventional. The present invention resides in the modification of the driver wheel 12 and certain other parts and the provision of a slide 43 which can be selectively controlled for closing the gate 12a in the driver wheel 12 so that a person not familiar with the combination cannot manipu-

late the dial 13 in any manner to give him a clue as to the combination of the lock. To this end, the outside of the driver wheel 12 has affixed thereto spaced guides 41 and 42. These guides are undercut as at 41a and 42a to provide marginal edges which overlap a slide 43. The slide 43 comprises an arcuate portion 43a which has exactly the same radius as the remaining peripheral surface of the driver wheel 12, two legs 43b and 43c and a second transverse portion 43d joining the opposite ends of the legs. The inner side of leg 43b is provided with gear teeth 44 which are adapted to mesh with a small pinion 46 to constitute a rack and pinion movement, the rotation of the pinion 46 controlling the radial movement of the slide 43. The pinion 46 is fixed to a shaft 47 which extends through a bore in the shaft 11. A pin tumbler lock 48 of conventional construction rotatably mounted in the hub of the dial 13, is fixed to the outer end of the shaft 47. As clearly shown in Figure 1, the barrel of the lock 48 is provided with a series of pins 51 of different lengths which are adapted to be aligned with a second plurality of pins 52 which are mounted in the radial recesses of the hub of the dial 13. The pins 52 are spring loaded so that they are normally urged toward the barrel of the lock in the usual manner. When the key 53 is not in the barrel, some of the pins 52 will extend across the dividing line between the barrel and the inside of the hub to provide an interlock between the barrel and the hub whereby the shaft 47 will be locked with the dial 13. Accordingly, rotation of the dial 13 will rotate the driver wheel 12 which in turn drives the tumblers in the manner already described. As in conventional cylindrical pin tumbler type locks, the key can only be removed and inserted when the tumbler is in one position. In the immediate instance the zero position of the lock is such that the pinion 46 will have moved the slide 43 to its radially outermost position where its outer arcuate surface 43a coincides with the outer periphery of the driver wheel 12. This is clearly shown in Figure 3. It will be readily seen that when the slide 43 is in this position the gate 12a is closed and the fence 21 can not fall or be urged by the spring 39 into the gates of the tumblers because the boss 28 of the fence-lever 24 will be prevented by the slide 43 from falling into its corresponding gate in the driver wheel 12. The size of the driver wheel 12 and the length of the boss 28 is such that the fence-lever 24 is held in such a position that the fence 21 cannot touch the tumblers unless the slide 43 is dropped to open gate 12a. However, assuming the gates of the tumblers are in registry, if now the key 53 is inserted in the lock 48 and shaft 47 is rotated to manipulate the pinion 46 to withdraw the slide 43 radially inwardly as shown in Figure 2, the fence will enter the gates so that the bolt 23 can be withdrawn by turning the driver wheel in a counter-clockwise direction as viewed in Figures 2 and 3. From Figures 1 and 2 it will be readily seen that the cover 1a of the casing is provided with suitable stops to limit the rotation of the driver wheel 12. As shown an arcuate boss 60 is provided, the edges 60a and 60b of which constitute the stops which limit the rotation of the driver wheel when the slide 43 is moved radially in such a position that the portion 43d of the slide projects beyond the outer periphery of the driver wheel 12. It will be seen that when the slide 43 is in the withdrawn position the driver wheel 12 cannot be rotated sufficiently to manipulate

the tumblers. However, the limits of rotation are such as to permit sufficient rotation of driver wheel 12 to withdraw bolt 23.

It will be apparent that the pin-tumbler lock 48 is not essential to the present invention; the lock 48 merely adds a measure of security because the slide control mechanism cannot be operated unless the shaft 47 is unlocked from the hollow shaft 11. On the other hand, if desired, a second combination could be substituted for the pin-tumbler lock 48.

The lock 48 does, however, add a real measure of security because the stops on the casing 1a permit rotation of the driver wheel 12 only over a limited arc, and should one be able to pick the lock 48 and drop the slide 43, the driver wheel 12 cannot be rotated sufficiently to manipulate the tumblers. Then in order to rotate the driver wheel 12 it is necessary to return the gate to original position and this will put the tumbler of lock 48 in such a position that it would again have to be picked in order to manipulate the tumblers 6, 7 and 8 and the slide 43 at the same time.

25 A modified form of the slide operating mechanism is shown in Figures 6, 7 and 8. In this form a special driver wheel 72 having the usual gate 80, is provided with laterally disposed undercut guides 72a and 72b. The undercut guides are adapted to receive the sides of a slide 73, the general outside shape of which is similar to the slide 43, previously described. One lateral edge of the slide is provided with an elongated recess 73a which is adapted to permit limited 30 relative movement with respect to a screw 74 in the driver wheel 72. The purpose of the screw and slot arrangement is to prevent the slide 73 from becoming disassembled from the guides on the sides of the driver wheel 72. The driver wheel 72 is provided with a recess 76 which is adapted to be engaged by a spring pressed ball 77. A suitable recess 78 in the lower end of the slide 73 is adapted to receive a spring 79 and the ball 77. It will be readily apparent that when the slide 73 is assembled under the lateral guides of the driver wheel 72 the spring 79 will press the ball 77 into the recess 76 when the slide is in one position.

It is important that the radii of the arcuate surfaces 73b and 73c of the slide 73 be exactly the same as the radius of the outer surface of the driver wheel 72. This will be apparent in view of the fact that the primary purpose of the slide 73 is to close the gate 80 of the driver wheel 72. It is important that when the slide 73 is in such position relative to the driver wheel 72 that the arcuate surfaces 73b and 73c be in registry with the periphery of the driver wheel 72 so there will be no unevenness in the surface on which the boss 28 of the fence-lever 24 rides and so that the position of the gate 80 will not be indicated in any manner by any manipulation of the driver wheel 72. It is to be understood that the driver wheel 72 is provided with a lateral 55 detent 22 through which the tumblers of the lock are to be operated in the manner previously mentioned.

As shown in dotted outline the cover for the casing is provided with inwardly projecting bosses 70 which limit the rotational movement of the driver wheel 72 when the slide 73 is in a position so that the arcuate surface 73c projects beyond the outer periphery of the driver wheel 72. The relative amount of limited rotation is the same

and for the same reasons as that described in connection with the first embodiment.

The construction of this modified form so far described is very similar to that of the previous form. The main difference between the two forms is that in the modified form the slide controlling mechanism is better adapted to the movements of the conventional pin tumbler type lock where the tumbler must be turned substantially 360° between the key-inserting position and the unlocking position. The main advantage of the modified form is that there is a minimum of lost motion between the cam and the gate when it is in the most essential position.

To this end, the slide 73 is provided with an opening 83 of the peculiar shape shown in the drawings. This opening 83 is adapted to cooperate with the slide cam 84 which is fixed to the end of the shaft 47 by means of a flattened area 47a and a complementary D-shaped hole 87 in the cam. The cam 84 is held on the end of the shaft 47 by means of the screw 88 which engages the end of the shaft. The opening 83 comprises an arcuate portion which extends between points 90 and 91, the radius of this portion being substantially the same as the radius of the outer surface 84a of the cam 84. The center of this radius is coincident with the center of the arcuate surface 84a when the slide 73 is in the position shown in Figure 6. The shape of the opening immediately below the point 91 is more or less immaterial so long as it clears the arcuate surface 84b. The rectangular recess 92 is of sufficient extent in both dimensions as to accommodate the entrance of the tang portion 85 of the cam 84.

For an explanation of the operation of the slide controlling mechanism of the modified form, attention is invited to Figures 6 and 7, 9, 10 and 11. In Figure 6 the slide 73 is shown in the depressed position permitting the boss 28 to drop into the gate 80 in the driver wheel 72 and with the tang 85 of the cam slide 84 in the position shown, the pin tumbler lock 48 will be in such a position to permit the insertion and removal of the key. In Figure 7 the slide 73 is shown in a position such that the arcuate surface 73b bridges the gate 80 so that the boss 28 holds the fence-lever 24 in the uppermost position with the fence 27 spaced from the outer periphery of the tumblers. When the slide 73 is in this position the driver wheel 72 can be rotated to all positions without the fence 27 dropping down on to the tumblers.

The progressive positions of the tang 85 in operating the slide 73 to open the gate 80 are shown in Figures 9, 10 and 11. Going back to Figures 6 and 7 it will be noted that in Figure 6 the slide 73 is in the lowermost position uncovering the gate 80 and the tang 85 is in the upper position. When the tang is in this position the pin tumbler of the lock 48 will be in such a position that the key can be inserted and removed. It will be noted that the slide cam 84 can be rotated in a clockwise direction and when the cam is rotated approximately ninety degrees the lower edge of the arcuate surface 84b will engage the underside of the notch 92 and the slide 73 will move toward the closed position. Continued rotation of the slide cam 84 in the clockwise direction, as shown in Figures 9 and 10, will cause the edge of the tang 85 to thereafter engage the underside of the notch 92 so that continued rotation will cause the slide to move toward the position shown in Figures 7 and 11 until the

surface 84a just clears the corner edge of the notch 92. At this point the slide 73 will be in the gate-closing position and the ball 77 will snap into the recess 76, thus holding the slide 73 in that position. The pin tumbler can be rotated further until the lower edge of the surface 84b engages the lower recess in the opening 83. It will be readily understood that when the tang 85 is rotated in counter-clockwise direction that the tang will engage the lower side of the notch 92 to move the slide to the lowermost position and the spring pressed ball will engage the driver wheel 72 thereby applying sufficient friction to hold the slide in the position so that the surface 73c projects beyond the periphery of the driver wheel 72.

When the slide 73 is in the latter position the sides of the slide will engage the edges of arcuate bosses 92 and 93 which are carried on the lock casing in the manner previously described. The purpose for limiting the rotation of the driver wheel is the same as that mentioned in connection with the previous embodiment.

In order to assure that the tumblers cannot be walked around by oscillating the driver wheel 72 through the limited arc permitted by the stop mechanism, the outer periphery of the tumblers are provided with continuous serrations 100 which are adapted to be engaged by a series of complementary serrations 101 on the underside of the fence 27. When the slide closes the gate in the driver wheel the boss 28 will prevent the fence from engaging the outer periphery of the tumblers and for purposes of illustration in the practical embodiment of the invention the fence 27 will be spaced about one-thirty-second of an inch from the outer edge of the serrations in the tumblers. As will be very clear from Figures 9 and 10, the outer periphery of the driver wheel 72 is provided with a relieved area 75 extending between the edge of the gate 80 and the slide 73. The purpose of this relieved area is to provide clearance between the boss 28 and the driver wheel 72 when the slide 73 is in the withdrawn position. Although the dimension is not absolutely critical in a practical embodiment of the invention the construction is designed so that there will be a clearance of about one-sixty-fourth of an inch between the boss 28 and the relieved area of the driver wheel periphery. It will be seen from this that no manipulation of the driver wheel 72 will make it possible to walk the tumblers in an attempt to open the lock. The engagement between the serrations on the fence 27 and the peripheries of the tumblers will insure that the tumblers cannot be rotated by any other means.

Figure 12 illustrates the manner in which the serrations on the underside of the fence 27 engage the serrations on one of the tumblers. It will be seen from this illustration that it would be extremely difficult for one not having the proper combination to locate the gates in the tumblers by partially withdrawing the slide 73 and attempting to oscillate the driver wheel. It will be seen that when the slide closes the gate 80 the fence 27 will be spaced from the tumblers and when the slide 73 is dropped so that the fence rests on the tumblers the boss 28 cannot touch the edge of the gate 80 in the driver wheel 72. The depth of the serrations is greater than the normal manufacturer's tolerance in the tumblers so that regardless of whether or not the gate-closing slide is used it would be extremely difficult to locate the gates in the tumblers by any kind of manipu-

lation of the driver wheel. It will be noted from Figure 12 that in view of the inclined surfaces on the lateral edges of the gate and on the fence it would be extremely difficult to note any difference in feel or any minute click unless the fence can drop all the way into the gates of the tumblers and, of course, this can happen only when all of the tumbler gates are in registry.

It is to be understood that the embodiment of the invention shown in Figures 1 to 5 inclusive is identical in operation and in general construction with that of the part of the invention shown in the remaining figures except for the mechanism which operates the slide 43 of the first embodiment and the slide 12 of the second embodiment. In other words, the driver wheel 12 of the first embodiment is provided with a relieved area 15 which corresponds to the relieved area 75 of the second embodiment.

Although the complete lock mechanism is not shown in connection with the modified form shown in Figures 6 to 11 inclusive, it will be understood that the lock would be substantially identical with the one previously described. It will also be apparent that instead of the pin tumbler lock 48, a combination type lock could also be used for controlling the mechanical connection between the hub of the dial 13 and the shaft 47. Furthermore, it will also be readily apparent from the above description that if desired a manually releasable mechanical connection could be provided between the hub of the dial 13 and the shaft 47 without utilizing a lock 48. For instance, a dog clutch could be provided so that normally the shaft 47 would rotate with the dial 13, the dog clutch being manually releasable so that the shaft 47 could be rotated independently of the shaft 11 for the purpose of controlling the position of the gate.

From the foregoing description it will be seen that the present invention provides an improvement in combination locks which greatly adds to the security thereof and which is very inexpensive to manufacture. Although the invention has been described in considerable detail, it will be apparent to those skilled in the art that many variations are possible without departing from the inventive concept. It is therefore desired that the invention not be limited except insofar as is made necessary by the appended claims.

What is claimed is:

1. A combination lock comprising selectively adjustable tumblers each having a peripheral recess, a bolt, a spindle having fixed thereto a driver wheel for adjusting said tumblers, a lever pivotally connected to said bolt, said lever having a laterally extending fence adapted to lie transversely across the faces of the peripheries of said tumblers and said lever also having a portion adapted to lie over and engage the periphery of said driver wheel, said driver wheel having a peripheral recess adapted to receive said portion of said lever to permit said fence to engage said tumbler recesses when the latter are adjusted to register with said fence for moving said bolt and interlock means normally preventing said fence from engaging said tumbler recesses during adjustment of the latter having actuating means selectively operative following adjustment of said tumbler recesses into registry for rendering said interlock means inoperative to prevent interengagement of said fence and tumbler recesses.

2. A combination lock comprising a plurality of selectively adjustable tumblers each having a

peripheral recess, a bolt, a spindle means having fixed thereto a driver wheel for adjusting said tumblers and for actuating said bolt, a lever pivotally connected to said bolt and having a tumbler-engaging fence and a driver wheel-engaging portion, said driver wheel having a peripheral recess adapted to receive said wheel-engaging portion of said lever when said recesses in said tumblers are adjusted to register with said fence, and means movably mounted on said driver wheel and intercoupled with said spindle means to be actuated therethrough for selectively bridging said peripheral recess in said driver wheel during adjustment of said tumblers.

15 3. The combination as set forth in claim 2, in which said bridging means is movable radially of said driver wheel.

4. The combination as set forth in claim 2, together with means for limiting rotation of said 20 driver wheel when said lever is engaged in said recess in said driver wheel.

5. A combination lock comprising selectively 25 adjustable tumbler wheels each having a recess in the periphery thereof, a bolt, a spindle means having affixed thereto a driver wheel provided with a peripheral recess for adjusting said tumbler wheels and for actuating said bolt, a lever pivotally connected to said bolt and engageable with said driver wheel for actuating said 30 bolt when said recesses in said tumbler wheels are adjusted to register with said fence, and means movably mounted on said driver wheel and intercoupled with said spindle means to be actuated therethrough for selectively barring engagement of said lever with the peripheral recess of said driver wheel during adjustment of said tumbler wheels and actuated through said intercoupling on registry of said tumbler wheels to permit said lever to engage said driver wheel peripheral recess.

40 6. The combination as set forth in claim 5, and means for limiting rotational movement of said driver wheel when said lever is engaged in said recess in said driver wheel.

45 7. A combination lock comprising selectively adjustable tumblers each having a peripheral recess, a bolt, a lever pivoted to said bolt, a spindle means provided with means for adjusting said wheels and for engaging said lever in one position for moving said bolt, said lever having a laterally 50 extending fence adapted to lie transversely of the peripheries of said tumblers and adapted to engage the recesses in said tumblers when the latter are in registry and interlock means intercoupled through said spindle means normally preventing said fence from engaging said tumbler recesses during adjustment of the latter to establish the combination, and actuated through said spindle means following alignment of said tumbler recesses to render the interlock means inoperative to bar interengagement of said tumbler recesses and fence.

60 8. A combination lock comprising selectively adjustable tumblers each having a peripheral recess, a bolt, a spindle having fixed thereto a driver wheel for adjusting said tumblers, a lever pivotally connected to said bolt, said lever having a laterally extending fence adapted to lie transversely of the peripheries of said tumblers and said lever also having a portion to lie over and engage the periphery of said driver wheel, said driver wheel having an annular peripheral portion and a relieved portion provided with a recess adapted to receive said portion of said lever 70 to permit said fence to engage said tumbler re-

75

11

cesses when the latter are adjusted to register with said fence for moving said bolt, the peripheries of said tumblers being provided with a continuous series of serrations and said fence being provided with serrations adapted to engage the serrations on said tumblers, the relationship of the annular peripheral portion of said driver wheel and said portion on said lever being such that when said portion engages said annular portion of said wheel the serrations on said fence will be disengaged from the serrations on said tumblers, said relieved portion being so proportioned as to permit engagement between said serrations on said fence and said tumblers while said portion on said lever clears said relieved portion.

9. A combination lock comprising a plurality of selectively adjustable tumblers each having a peripheral recess, a bolt, a hollow spindle having fixed thereto a driver wheel for adjusting said tumblers and for actuating said bolt, a lever pivotally connected to said bolt and having a tumbler engaging fence and a driver wheel engaging portion, said driver wheel having a peripheral recess adapted to receive said wheel engaging portion when said recesses in said tumblers are adjusted to register with said fence, a shaft extending through said spindle and means operably associated with said shaft for selectively bridging said peripheral recess in said driver wheel.

10. A combination lock comprising a plurality of selectively adjustable tumblers each having a peripheral recess, a bolt, a hollow spindle having fixed thereto a driver wheel for adjusting said tumblers and for actuating said bolt, a lever pivotally connected to said bolt and having a tumbler engaging fence and a driver wheel engaging portion, said driver wheel having a peripheral recess adapted to receive said wheel engaging portion when said recesses in said tumblers are adjusted to register with said fence, said driver wheel having a bridging slide movable radially of said wheel, said slide having an arcuate surface adapted to bridge said peripheral recess in said driver wheel, a shaft extending through said hollow spindle and means operably associated between said shaft and said slide for moving the latter radially of said wheel.

11. A combination lock comprising a casing adapted to be attached to a door, said lock comprising selectively adjustable tumblers each having a peripheral recess, a locking bolt, a spindle projecting from said casing and adapted to extend through said door, the outer end of said spindle having secured thereto a manually op-

erable dial, the other end of said spindle having fixed thereto a driver wheel for adjusting said tumblers and for actuating said bolt, a lever pivotally connected to said bolt and having a tumbler engaging fence and a driver wheel engaging portion, said driver wheel having a peripheral recess adapted to receive said wheel engaging portion of said lever when said recesses in said tumblers are adjusted to register with said fence, means for selectively bridging said peripheral recess in said driver wheel, a shaft extending through said spindle and operably associated with said means for selectively bridging said recess in said driver wheel.

12. A combination as set forth in claim 11, plus means for locking said shaft to said hollow spindle.

13. A combination lock comprising a casing adapted to be attached to a door, said lock comprising selectively adjustable tumblers each having a peripheral recess, a locking bolt, a spindle projecting from said casing and adapted to extend through said door, the outer end of said spindle having secured thereto a manually operable dial, the other end of said spindle having fixed thereto a driver wheel for adjusting said tumblers and for actuating said bolt, a lever pivotally connected to said bolt and having a tumbler engaging fence and a driver wheel engaging portion, said driver wheel having a peripheral recess adapted to receive said wheel engaging portion of said lever when said recesses in said tumblers are adjusted to register with said fence, said driver wheel having a slide movable radially of said driver wheel, said slide having an arcuate portion of the same radius as the outer periphery of said driver wheel and adapted to bridge said recess in said driver wheel when in one position, a shaft extending through said spindle, means operably associated between said shaft and said slide for causing radial movement thereof and locked means for fixing said shaft for selectively fixing said shaft for rotation with said spindle.
